UNITED STATES PATENT OFFICE.

PETER FRANTZ, OF MOUNT MORRIS, ILLINOIS.

DESIGN FOR A FENCE-STAY.

SPECIFICATION forming part of Design No. 27,073, dated May 18, 1897.

Application filed April 3, 1897. Serial No. 630,659. Term of patent 14 years.

To all whom it may concern:

Be it known that I, PETER FRANTZ, a citizen of the United States, residing at Mount Morris, in the county of Ogle and State of Illinois, have 5 invented and produced a certain new and useful Design for Fence-Stays; and I do hereby declare the following to be a specification of the same, reference being had to the accompanying drawings, forming a part hereof, in 10 which—

Figure 1 is a perspective view of a fence-stay, showing my design. Fig. 2 is a side elevation of the same.

The leading feature of my design is the 15 shape or conformation.

The stay is formed in a single piece of wire having the shank portion 1, a hook 2 formed at one end, and an eye 3 at the other end. The hook 2 is formed in the lengthwise direction of the shank and the eye substantially 20 at right angles thereto. The lower portion of the shank is curved, as shown at 4.

I claim as my invention—

The design for a fence-stay substantially as shown and described.

PETER FRANTZ.
